(57) CLAIM

The ornamental design for a coin box organizer, as shown and described.

DESCRIPTION

FIG. 1 is an exploded perspective view of a first embodiment of a coin box organizer showing our new design, shown in an open configuration with the bottom drawer coin holder removed;

FIG. 2 is a perspective view of FIG. 1, shown in an open configuration with the bottom drawer coin holder inserted; FIG. 3 is another perspective view of FIG. 1, shown in a closed configuration;

FIG. 4 is a front elevational view of FIG. 3;

FIG. 5 is a rear elevational view of FIG. 3;

FIG. 6 is a top plan view of FIG. 3;

FIG. 7 is a bottom plan view of FIG. 3;

FIG. 8 is a left side elevational view of FIG. 3;

FIG. 9 is a right side elevational view of FIG. 3;

FIG. 10 is an exploded perspective view of a second embodiment of a coin box organizer showing our new design, shown in an open configuration with the bottom drawer coin holder removed;

FIG. 11 is a perspective view of FIG. 10, shown in an open configuration with the bottom drawer coin holder inserted; FIG. 12 is another perspective view of FIG. 10, shown in a closed configuration;

FIG. 13 is a front elevational view of FIG. 12;

FIG. 14 is a rear elevational view of FIG. 12;

FIG. 15 is a top plan view of FIG. 12;

FIG. 16 is a bottom plan view of FIG. 12;

FIG. 17 is a left side elevational view of FIG. 12; and,

FIG. 18 is a right side elevational view of FIG. 12.

1 Claim, 18 Drawing Sheets
